REFRIGERATING APPARATUS

Willard L. Morrison, Chicago, Ill., assignor to
Dole Valve Company, Chicago, Ill.

Application August 31, 1932, Serial No. 631,138

6 Claims. (Cl. 62—126)

This invention relates to refrigerating apparatus and has for its object to provide a new and improved device of this description. The invention has as a further object to provide a refrigerating apparatus wherein the refrigerating effect is produced directly from a primary refrigerating surface. The invention has as a further object to provide a flat primary refrigerating surface made up from a hollow coiled pipe containing refrigerant. The invention has as a further object to provide a freezing unit made from a coiled pipe, which freezing unit has a flat refrigerating face. The invention has other objects which are more particularly pointed out in the accompanying description.

Referring now to the drawings, Fig. 1 is a view showing one form of refrigerator embodying the invention, the parts being broken away to show the interior construction;

Fig. 2 is an enlarged view of a portion of the device shown in Fig. 1, with parts broken away;

Fig. 3 is a sectional view taken on line 3—3 of Fig. 2;

Fig. 4 is a front view of the refrigerating coil after it has been completed;

Fig. 5 is an enlarged view showing the method in which the coil is bent to produce the refrigerating plate;

Fig. 6 is an enlarged perspective view of the water freezing section, with parts omitted;

Fig. 7 is an enlarged sectional view taken on line 7—7 of Fig. 6;

Fig. 8 is a view of a portion of the device showing the method of bending when two coils side by side are used.

Like numerals refer to like parts throughout the several figures.

My present invention is applicable to refrigerators of various kinds and sizes, and is also applicable to the water freezing units used in refrigerators. I have illustrated it in the drawings as applied to a main refrigerator and to a water refrigerating unit therein.

Referring to the drawings, I have shown a refrigerator 1, having an insulated lining 2 of any suitable material. Located within the insulated lining is a refrigerating element 3 through which the refrigerant is circulated, the refrigerant entering the refrigerating element through a pipe 4 and passing therefrom through a pipe 5. These pipes are connected to a suitable refrigerating machine, not shown.

The refrigerating element is made up from a flat pipe 6 of square or rectangular cross section formed into any desired shape, with the edges of

the pipe abutting. In Fig. 5 I have shown one construction where the flat pipe is wound so as to form a refrigerating element like the refrigerating element 3 shown in Fig. 1; that is, it is wound so as to have a hollow interior into which the materials to be cooled may be placed. This flat pipe, after it has been formed into the desired form, is then coated or plated with a thin coat 6a of conducting material, such as tin, which fills up the connections at the points where the edges of the pipes abut so as to make a smooth, even, continuous, unbroken surface on the inner and outer faces of the refrigerating element. Fig. 7 shows this on an enlarged scale, and Fig. 6 shows how the exterior of the elements would look.

If tin is to be used, the element, after being made, may be immersed in a bath of tin, it being first treated in the ordinary way so that the tin will properly adhere thereto. In Fig. 5 I have shown only a few coils of the pipe for purposes of illustration, in order to show how the refrigerating element is made. The refrigerant is admitted to the flat pipe by an admission pipe 4 and is discharged therefrom through a pipe 5. In Fig. 4 I have shown the refrigerating element 3 separate from the refrigerator. This refrigerating element may, if desired, have suitable shelves on the interior thereof and it lends itself readily to various forms of shelves. I have shown, for example, the shelf supports as being made of angle irons 3a located at suitable intervals, and the shelves 3b resting thereon so that they are easily removable.

This refrigerating element may also be used for the water freezing element in a refrigerator made as herein shown, or a refrigerator of any other type or form. For this purpose the flat pipe is formed into a tray receiving refrigerating element 7 which is coated or plated with a thin coat of metal, as hereinbefore set out, which may be supported in the refrigerator in any desired manner and which is preferably provided with tray supports 8 which support the water trays 9. These tray supports 8 may be angle irons, as shown, or of any other form desired. The refrigerant is circulated through the refrigerating element, entering by means of the pipe 10 and being discharged through the pipe 11. The water freezing element 7 may be supported in the refrigerator in any desired manner, and I have shown a simple construction in which there is attached to the top of the water freezing element a supporting member 12 which has the lateral extensions 13 which fit on the inwardly projecting portions 14 of a supporting

member 15 attached to some suitable part of the refrigerator. One form of this water freezing element 1 is shown in perspective in Fig. 6. If desired, the refrigerating element may be made of a plurality of flat pipes formed into the desired shape. In Fig. 8 I have shown a form wherein there are two separate flat pipes 16 and 17 placed side by side and bent so as to form a hollow metal receiving refrigerating element similar to that shown in Figs. 1, 4, 5 and 6.

It will be seen that by means of this construction I am enabled to form a refrigerating element which will have flat, smooth refrigerating surfaces which are primary refrigerating surfaces, that is the refrigerating surface being the surface of the pipe through which the refrigerant is circulated. I have found that with a flat, smooth refrigerating surface of this type, whatever frost accumulates is easily and quickly removed, for if the device is heated for a short time it slides off, whereas with a construction with a roughened surface or with coils the removal of the frosting requires a long time. This flat surfaced refrigerating element is of an exceedingly high efficiency, because the refrigerating surface is the primary refrigerating surface, being the flat surface of the coil through which the refrigerant is circulated. This continuous, flat primary refrigerating surfaced refrigerating element has advantages in addition to its high refrigerating efficiency. It is of course evident that the coating may be omitted if desired. In that event the element would have a surface like that shown in Fig. 5.

The use and operation of my invention are as follows:

When the coils are properly shaped into the refrigerating element and placed in the refrigerator, or when they are shaped into a freezing element, the refrigerant is circulated through the coils and the primary refrigerating surface then acts upon the material in the refrigerator. When the coils are used as a water freezing element, the refrigerant is circulated therethrough and the receptacles containing the water are placed in position so that the water will be frozen by the action of the primary refrigerating surface of the refrigerating element.

The outer and inner surfaces are both refrigerating surfaces. I have found, for example, that in an ordinary refrigerator it is only necessary to use the ice refrigerating element 1. The inner refrigerating surface freezes the water, and the outer refrigerating surface cools the interior of the refrigerator as it does not require a freezing temperature. In an ordinary refrigerator, therefore, the refrigerating element 3 would be omitted and only the refrigerating element 1 used.

Referring to Fig. 7, for purposes of illustration I have shown the coating 6a as of a thickness to be easily visible, but it is of course evident that this coating would be very thin and that this thickness in Fig. 7 is exaggerated for purposes of illustration.

I claim:

1. An air contacting refrigerating element comprising a flat faced pipe bent to form a coil with the edges of the pipe abutting, the flat faces of the adjacent portions of the pipe being in

substantially the same plane so as to form a flat faced refrigerating element with a flat primary refrigerating surface with which the air comes in contact, the material to be cooled being placed in vessels separate from the refrigerating element.

2. A refrigerating element comprising a flat faced pipe bent to form a coil with the edges of the pipe abutting, the flat faces of the adjacent portions of the pipe being in substantially the same plane so as to form a flat faced refrigerating element with a flat primary refrigerating surface to which the material to be acted upon is exposed, the refrigerating surface of the coil being covered with a thin coating of conducting material so as to form a continuous unbroken refrigerating surface across the several sections of the pipe.

3. A refrigerating element comprising an insulating casing, a flat faced pipe within said insulating casing bent to form a coil with the edges of the pipe abutting, the flat faces of the adjacent portions of the pipe being in substantially the same plane so as to form a flat faced refrigerating element with a flat primary refrigerating surface to which the material to be acted upon is exposed, the coil formed by said pipe being of a rectangular shape, having flat, smooth vertical sides to prevent ice from accumulating thereon.

4. A refrigerating element comprising a flat faced pipe bent to form a coil with the edges of the pipe abutting, the flat faces of the adjacent portions of the pipe being in substantially the same plane so as to form a flat faced refrigerating element with a primary refrigerating surface to which the material to be acted upon is exposed, there being two inner opposed flat continuous surfaces with supports on the opposed inner cooling faces of said surfaces, and water receptacles slidably carried by said supports.

5. An air contacting refrigerating element comprising a flat faced pipe bent to form a coil with the edges of the pipe abutting, the flat faces of the adjacent portions of the pipe being in substantially the same plane so as to form a flat faced refrigerating element with a primary refrigerating surface with which the air comes in contact, the material to be cooled being placed in vessels separate from the refrigerating element, a thin coating of heat conducting material on the refrigerating surface of the coil and extending across the points where the edges of the pipe abut so as to form a continuous refrigerating surface.

6. A refrigerating element comprising a flat faced pipe bent to form a coil with the edges of the pipe abutting, the flat faces of adjacent portions of the pipe being substantially in the same plane, said coil formed into a continuous enclosing device having a top, bottom and two sides with a receiving space between them, opposed supports directly connected with the pipe on the opposed inner cooling faces thereof and projecting inwardly therefrom, and removable devices interposed between the opposed supports and carried by said supports.

WILLARD L. MORRISON. 70
